US00D887144S

(12) **United States Design Patent** (10) Patent No.: **US D887,144 S**
Xi et al. (45) Date of Patent: **** Jun. 16, 2020**

(54) **ORAL CARE IMPLEMENT**

(71) Applicant: **Colgate-Palmolive Company**, New York, NY (US)
(72) Inventors: **Wen Jin Xi**, Shanghai (CN); **Robert Moskovich**, Manakin-Sabot, VA (US); **Guang Sheng Guo**, Yangzhou (CN); **Stephen Nelson**, New Brunswick, NJ (US); **Joachim Storz**, Zell am See (AT); **Felix Mueller**, Zell am See (AT)

(73) Assignee: **Colgate-Palmolive Company**, New York, NY (US)

(**) Term: **15 Years**

(21) Appl. No.: **29/673,406**

(22) Filed: **Dec. 14, 2018**

Related U.S. Application Data

(60) Continuation of application No. 29/586,629, filed on Dec. 6, 2016, now Pat. No. Des. 840,691, which is a division of application No. 29/533,922, filed on Jul. 23, 2015, now Pat. No. Des. 777,446.

(51) LOC (12) Cl. **04-02**
